UNITED STATES PATENT OFFICE.

ARTIUR MARTIN, OF PARIS, FRANCE.

DESIGN FOR WALL-PAPER.

SPECIFICATION forming part of Design No. 28,111, dated December 28, 1897.

Application filed October 26, 1897. Serial No. 656,470. Term of patent 7 years.

To all whom it may concern:

Be it known that I, ARTHUR MARTIN, of Paris, France, have invented and produced a new and original Design for Wall-Paper, of which the following is a full, clear, and exact specification, reference being had to the accompanying drawing, forming a part thereof, in which is represented a plan view of a fragment of wall-paper embodying the new design.

The design is especially applicable to wall-papers and to that class of wall-papers which imitates leather.

The leading feature of the design, which is produced upon the wall-paper X, consists of a shield A, having scroll extensions and which bears a panel decorated with interlocked horns. The shield is within an irregular border A', the opposite sides of the border being twice crossed beneath the shield, forming two panels *a* and *a'*. At each side of the panel *a* scroll-shields B and B' are arranged, the scroll-shield B being decorated with a foliate figure and the opposing scroll-shield B' bearing the crossed horns above referred to. The crossed portions of the border forming the lower panel *a'* are carried outward in opposite directions to form a duplication of the upper portion of the border A', the lower and duplicated portion of said border being designated as A². Foliate branches C extend from the border A² through the members of the shields B and B' back of the upper portion of the border designated as A', and where the

foliate branches pass the upper border A' 35 they converge and pass between the extensions of the main upper shield A. Sub-branches are extended from the main foliate branches C, where the said main foliate branches are passed through the upper shield 40 A. A garland of flowers D connect the upper portion of the foliate branches C, the said garland being above the main shield A. Below the main shield A and above the first crossing of the border A' a floral figure is produced, together with the representation of fruit, and in the panel *a* a basket is made to appear containing sundry flowers, some of which extend beyond the portions of the border forming said panel. In the panel *a'* a 50 garland of fruit is shown, and the said garland of fruit is apparently supported by foliate scrolls E, which apparently pass through the extensions of the shields B and B' and extend to the lower border portion A². 55

Another feature of the design consists in groups of fruit, which apparently extend from the foliage of the stems C at each side of the main panel A and interlocking the floral branches, which appear in a measure entwined 60 with foliate extensions from the stems C.

I claim—

The design for wall-paper herein shown and described.

ARTHUR MARTIN.
